UNITED STATES PATENT OFFICE.

FRANK L. BURKE, OF CONNERSVILLE, INDIANA, ASSIGNOR, BY DIRECT AND MESNE ASSIGNMENTS, OF ONE-HALF TO INDIANA LAMP CORPORATION, OF CONNERSVILLE, INDIANA, A CORPORATION OF DELAWARE, AND ONE-HALF TO GENERAL MOTORS CORPORATION, OF DETROIT, MICHIGAN, A CORPORATION OF DELAWARE.

HEADLAMP REFLECTOR.

Application filed February 16, 1924. Serial No. 693,309.

To all whom it may concern:

Be it known that I, FRANK L. BURKE, a citizen of the United States, and a resident of Connersville, county of Fayette, and State of Indiana, have invented certain new and useful Improvements in Headlamp Reflectors, of which the following is a full, clear, concise, and exact description, such as will enable others skilled in the art to 5 which the invention relates to make and use the same, reference being made therein to the accompanying drawings, which form a part of this specification.

This invention relates to reflectors, and 10 is illustrated as embodied in a reflector for an automobile headlamp.

An object of the invention is to provide a single reflector for a plurality of electric bulbs or other sources of light, which will 15 efficiently reflect the light of each source in a manner which permits control of the light to secure adequate road illumination, while at the same time diffusing the light rays in such a way as to avoid glare.

20 In one desirable arrangement, intended for use with driver-controlled bright and dim bulbs, to permit dimming of the headlights at will, the reflector has different sections especially designed for controlling the rays of the corresponding lights, to give 25 carefully controlled and adequate illumination, the section corresponding to the idle light being out of focus with respect to the light which is on at any time, and therefore 30 reflecting its rays in a softly diffused manner.

35 Preferably, the reflector is divided into a series of vertical zones, each having its horizontal elements substantially straight to 40 give a very narrow beam of rays which are slightly divergent, and which can therefore be accurately controlled by the position of a perpendicular to such elements, as compared to the center line of the reflector. 45 The vertical center line of each vertical zone is in upper and lower sections, the upper section being part of a parabola, or other conic section approximating a parabola, with its focus at the center of the filament 50 of the upper bulb, and the lower section being a similar part of a conic section with its focus at the center of the filament of the lower bulb.

The above and other objects and features of the invention will be apparent from the 55 following description of one illustrative embodiment shown in the accompanying drawings, in which—

Fig. 1 is a front elevation of a reflector; 60 and

Fig. 2 is a vertical section on the line 2—2 of Fig. 1.

In the drawings, for purposes of illustration, the reflector is shown as of metal, having a bezel 10 and a reflector portion proper 65 12. Sockets 14 and 16, vertically spaced above one another, are provided for bright and dim electric bulbs projecting horizontally forward into the reflector, these sockets being substantially equidistant from a 70 central horizontal plane A—A, and in the central vertical plane passing through the section line 2—2.

As explained above, the reflecting surface 75 is broken up into a series of vertical zones 18, eleven such zones being shown. The horizontal elements of each zone, i. e. the intersections with horizontal planes, are substantially straight lines, to give the desired controlled diffusion of the light rays. If 80 desired, these elements might be curved, as, for example, as short sections of parabolas, the essential point for the purpose being that there shall be a distinct angle between adjacent zones, so that the direction and 85 diffusion of light reflected by the several zones may be independently controlled.

The center line of each zone 18 may be 90 regarded as comprising two sections, one above and one below the plane A—A. The upper section of this center line is shown as being a parabola with its focus at the filament of the upper light,—that is to say, the parabola and opening 14 are coaxial, so that the vertex of the parabola comes at the center of the opening. Similarly, the lower section is a parabola with its focus at the filament of the lower light, coaxial with opening 16, and with its vertex at the center 95 of the opening. The two parabolas intersect in the plane A—A, the upper one extending below its vertex and the lower one extending above its vertex.

100 While one illustrative embodiment of the invention has been described in detail, it is 105 not my intention to limit its scope to that

embodiment, or otherwise than by the terms of the appended claims.

I claim:

1. A headlamp reflector having two vertically-spaced foci substantially in its central plane, and formed with two openings for bright and dim electric bulbs with their filaments respectively at the different foci, each opening being directly behind and in an axis passing through the corresponding focus, the internal surface of the reflector being formed in a series of vertical zones having straight elements in horizontal planes and being curved in vertical section in such a manner that the center line of the upper half of each zone is a section of a parabola described about the upper focus and with its vertex in the upper axis and extending below the said vertex, and the center line of the lower half of each zone is a section of a parabola described about the lower focus and with its vertex in the lower axis and extending above the said vertex, the junction of the upper and lower halves of each zone being in a horizontal plane substantially midway between the two axes.
2. A headlamp reflector having two vertically-spaced foci substantially in its central plane, and formed with two openings

for bright and dim electric bulbs with their filaments respectively at the different foci, the internal surface of the reflector being formed in a series of vertical zones forming distinct horizontal angles with each other and being curved in vertical section in such a manner that the center line of each zone is in its upper portion a conic section described about the upper focus and with its vertex in an axis passing through the upper opening and extending below the said vertex, and is in its lower portion a conic section described about the lower focus and with its vertex in a lower axis passing through the lower opening and extending above the said vertex.

3. A headlamp reflector having two parabolic sections arranged one above the other and meeting in a horizontal plane beneath the vertex of the upper section and above the vertex of the lower section, each section having means for supporting a lamp bulb in the axis of the curve, and each section being formed of a series of narrow flat parallel zones meeting in vertical planes at a distinct angle.

In testimony whereof I affix my signature.

FRANK L. BURKE.
